M. STEIN,
ACETYLENE LAMP,
APPLICATION FILED OCT. 14, 1919.

1,376,654.

Patented May 3, 1921.

INVENTOR
MEYER STEIN,
by James L. Hopkins ATTORNEY.

UNITED STATES PATENT OFFICE.

MEYER STEIN, OF SPRINGFIELD, ILLINOIS, ASSIGNOR OF ONE-HALF TO PHILIP STEIN, OF SPRINGFIELD, ILLINOIS.

ACETYLENE-LAMP.

1,376,654.

Specification of Letters Patent.

Patented May 3, 1921.

Application filed October 14, 1919. Serial No. 330,549.

To all whom it may concern:

Be it known that I, MEYER STEIN, a citizen of the United States of America, residing at Springfield, in the county of Sangamon and State of Illinois, have invented certain new and useful Improvements in Acetylene-Lamps, of which the following is a specification, reference being had therein to the accompanying drawing.

10 My invention relates to improvements in acetylene lamps and more particularly to the dropper, or valve controlled communication, between the water and carbid containers.

15 My object is to provide a dropper, of simple construction, in which the valve may, with facility, be removed for purposes of cleaning and repair.

20 My improvements consist in the novel construction, arrangement and combination of parts, as will hereinafter be fully, clearly and concisely set forth, definitely pointed out in my claim and illustrated by the accompanying drawing, in which—

25 Figure 1 is a vertical sectional elevation of an acetylene lamp constructed in accordance with my invention.

Fig. 2 is a perspective view of my improved, removable and replaceable valve-stem, and

Fig. 3 is a perspective view of the manipulative element of the dropper.

Referring to the drawings, by numerals, 4 designates the water container and 5 the carbid container, located beneath the water container 4 and detachably secured thereto, as by threads 6.

40 In the septum 7 dividing the containers 4 and 5 there is a port 8, over which there is a water tight hood 9 which port and hood form a gas communication, through the water container, between the carbide container and the jet 10.

45 Through the top of the water container there is a filling opening 11, having a cover 12.

Extended through the top of the water container and through the septum 7, there is the dropper, which comprises an open 50 ended tube 13 having a hole 14 communicating with the water container and which is

internally threaded, as at 15, at its upper end, and which is preferably secured in place, against removal, as by solder, or the like, at the top of the water container and at 55 the septum.

Extended through the tube 13 and projecting at both ends therefrom is a stem 16, which is threaded at both its ends and provided adjacent its upper end with a pair of 60 swaged wings 17, which serve as keys to prevent relative rotational movements between the stem and its raising and lowering means, namely the externally threaded sleeve 18 having the slots 19 for fitment over the 65 wings 17 of the stem, and which is threaded to the threads 15 of the tube 13. The stem 16 is of the form illustrated in Fig. 2, having both its upper and lower terminals threaded, and having its body flattened to 70 form the wings 17—17.

For holding the stem 16 and tube against relative longitudinal or vertical movement I provide a nut 20 threaded upon the stem for engagement with the sleeve to hold their 75 keying devices, the wings 17 and slots 19 in locked relationship.

For convenience in rotating the sleeve to raise and lower the stem I provide a handle 21, which by preference is permanently secured to the sleeve and which handle, by further preference, is constructed of an elastic metal, such as sheet brass, whereby to operate as a tension device, to hold the sleeve against ready rotation, as required 80 to maintain an established water flow.

To the lower threaded end of the stem there is secured a valve 22, provided with a flange 23, and with a cone 24, which operates with the lower end of the dropper tube 90 to control the flow or dropping from the water container to the carbide container.

It will be obvious that upon a release of the nut 20, from the stem 16 that the stem, with its valve 22, may be bodily removed 95 from the tube 13, by a simple withdrawal of the wings 17 from the slots 19 of the sleeve, and that with the stem and valve removed the tube, open at both ends may be readily cleaned, or freed from matter tending to prevent proper operation of the valve. 100

I claim:

A dropper for acetylene lamps, comprising a tube, open at both ends, a sleeve having a threaded connection with the tube, a 5 stem extended through the tube and sleeve, a valve carried by the stem, means for keying the stem to the sleeve, a handle for ro-

tating the sleeve and a nut for holding the sleeve and stem with their keying means relatively engaged.

In testimony whereof I hereunto affix my signature.

MEYER STEIN.
